WIRE SPlicer

Laudie E. Krosman, Scio, Oreg.

Application March 15, 1933, Serial No. 660,918

7 Claims. (Cl. 140—118)

My invention relates to wire-working tools, and particularly to a tool for splicing together the ends of wires.

An important object of my invention is to provide a tool of the character described which is simple and efficient and cheap to manufacture, and which can be used by persons unskilled and unpracticed in wire splicing to produce with little effort on the part of the operator, uniform splicings which form a strong and enduring connection between the wire-ends.

Other objects and advantages of my invention will be apparent from a reading of the following description in connection with the drawing, wherein for purposes of illustration I have shown a preferred embodiment of my invention.

In the drawing:—

Figure 1 is a perspective view of the embodiment showing the same in the condition in which it is initially applied to a pair of wire-ends, which are shown in dotted lines.

Figure 2 is a perspective view showing the tool in use.

Figure 3 is a side elevational view of the embodiment.

Referring in detail to the drawing, wherein like numerals refer to like parts throughout the same, the numeral 5 refers generally to the elongated rectangular block which may be conveniently made of cast metal and of suitable cross-section.

Close to one side of the top of the block and extending from one end thereof to a central point of the block in the wire-end receiving groove 6 whose inward end opens is a rounded or substantially semi-cylindrical recess 7 which opens through the said one side and top of the block. The bottom of the inner end portion of the groove 6 is angularly depressed as indicated at 6a in Figure 3.

Traversing the top of the block 5 approximately at the center thereof is a second wire receiving groove 8 of approximately the same depth and size as the groove 6 and opening at its ends through the opposite sides of the block. One end of the groove 8 opens as indicated at 9 into the recess 7 while the opposite end of the groove 8 opens as indicated at 10 through the apex of a triangular lateral extension 11 on the side of the block opposite the recess 7.

A pivot such as a screw 12 is located near the recess 7 on the side of the groove 8 opposite the position of the groove 6, and this forms the pivotal mounting for a swingable closure member designated 13 which is arranged to swing back and forth across the block.

The closure 13 comprises a flat rectangular metallic plate through one corner of which the screw pivot 12 passes. The plate is about the same width as the block 5 so that when it is swung into the closed position shown in Figure 2 it substantially coincides with the portion of the top of the block on which it is then superposed. The plate 13 has a triangular lateral extension 14 of the same size and dimensions as the lateral extension 11 of the block so that the portion 14 coincides with the extension 11 when the plate 13 is in its closed position. The free end of the plate has a portion severed as indicated at 15 and the separated portion turned upwardly and over to provide the handle 16. The edge 17 of the plate is provided with a small rectangular notch 18 intermediate its ends, and between the notch and the pivot it is provided with a larger rectangular notch 19 of a width approximately equal to that of the recess 7 which it exposes, these notches enabling seeing the length of wire left in the groove 6 and in the recess 7 during the splicing without disturbing the plate 13 from its closed position.

The wire-ends to be spliced are laid along the groove 8 in side by side manner. Then one of the wires is bent laterally with a pliers or any other suitable means and then placed into the groove 6 as indicated at 20 in Figure 1. The other wire 21 is left in the groove 8. Then the closure plate 13 is swung from the open position shown in Figure 1 to the closed position shown in Figure 2 in which it holds the wires 20, 21 in their respective grooves. Then a pliers or the like generally designated 22 is used to grasp and clamp the wire ends 23, 24 which are then extending from the recess 7 at points inward of their respective terminals, so that the wire portions 23, 24 are held in side by side relationship as shown. Then the block 5 is rotated in one direction while the pliers 22 is held still, so as to wind or coil the wire end 20 upon the wire end 21. When this has been accomplished, the closure 13 is opened and the tool removed from the wires and then the wire end 24 is laid in the groove 6, and the wire end 23 in the groove 8. The tool being then in a position reversed with respect to the first described position is then rotated until a second coil like that generally designated 25 in Figure 2 is completed, whereupon the wire-ends will have been accurately, uniformly, strongly, and inseparably spliced. With this arrangement of the wire-ends, the stronger the pull upon the wires, the stronger the connection between the wire ends becomes.

It will be observed that the inner side of the groove 6 where it merges into the recess 7 is in substantially the same plane as the inner end of the recess 7, so that the wire moving from the groove 6 into the recess 7 moves into engagement with the said inner end of the recess. Supposing that a preceding convolution of the coil being made is in existence, such convolution will coat with the inner end of the recess in determining the formation of the next convolution, by confining the portion of the wire in process of being formed into a succeeding convolution, into a certain form and curvature. The curved wall of the recess also assists this formation process. The result of the coactions just described is production of uniformly curved and spaced convolutions.

It will be obvious that linesmen, farmers, and other persons who are frequently called upon to splice wire-ends, will find that the device of the invention saves time and labor, and is productive of more efficient and uniform work, and that the use of the device of the invention prevents those injuries to the hands which are common in wire splicing operations when conducted with the hands and hand tools heretofore employed for this service.

Although I have shown and described herein a preferred embodiment of my invention, it is to be definitely understood that I do not desire to limit the application of the invention thereto and any change or changes may be made in materials, and in the structure and arrangement of the parts, within the spirit of the invention and the scope of the subjoined claims.

What is claimed is:—

1. A wire splicer comprising a block having in one side a pair of straight wire end receiving grooves located in approximately the same plane and intersecting approximately at right angles, and a relatively thin closure plate mounted on the block and swingable transversely on said side of the block for positioning over the grooves for holding the wire ends in the grooves.
2. A device for splicing a pair of wires in a continuous helical coil, said device comprising an elongated block formed with a transverse groove of substantially semi-circular cross section in its top intermediate its ends, the opposite ends of said transverse groove opening through the opposite sides of the block, the opening at one end of said groove being concentrically enlarged in diameter and forming a substantially semi-cylindrical recess extending inwardly with respect to the side of the block, said top of the block being formed with a longitudinal groove of semi-circular cross section extending along and close to the last mentioned side of the block, the outer end of said longitudinal groove opening through the end of the block and the inner end of said longitudinal groove opening through the side of said recess, whereby a wire lying in said longitudinal groove and bent substantially at right angles in said recess so as to have a portion extending outwardly from the block and a second wire lying in said transverse groove and alongside of said portion of the wire may be coiled continuously upon each other by rotating said block on the axis of the second wire while said portion of the first wire and said second wire are held in side by side relation, and a short closure plate

hinged to an intermediate part of said top of the block and arranged to be swung into and out of closing relation to one or both of said grooves, the side of said closure plate covering said longitudinal groove being provided with openings spaced longitudinally with respect to said longitudinal groove for indicating the length of unused wire left in said longitudinal groove and in said recess during the progress of the splicing. 5

3. A tool for coil-splicing two wire ends, said 10 tool comprising a block having in one side two intersecting wire end receiving grooves, said grooves lying in approximately the same plane, a closure plate pivoted on said side of the plate for swinging in a plane parallel to the first men- 15 tioned plane and into and out of closing relation to said grooves.

4. A tool for coil-splicing two wire ends, said 20 tool comprising a block having a substantially flat top formed with a pair of intersecting wire end receiving grooves, and a plate on said top for closing said grooves, said plate being pivoted on an axis substantially right angularly related to said top.

5. A tool for coil-splicing two wire ends, said 25 tool comprising a block having a substantially flat top formed with a pair of intersecting wire end receiving grooves, and a plate on said top for closing said grooves, said plate being pivoted on an axis substantially right angularly related to 30 said top, one of said grooves lying along and close to one side of said top and intersecting the remaining groove at a point close to said side of the top, the junction of said grooves being enlarged to provide a coil forming chamber extending 35 axially outward through the side of the block with respect to said remaining groove.

6. A tool for coil-splicing two wire ends, said 40 tool comprising a block having a substantially flat top formed with a pair of intersecting wire end receiving grooves, and a plate on said top for closing said grooves, said plate being pivoted on an axis substantially right angularly related to said top, one of said grooves lying along and close to one side of said top and intersecting the re- 45 maining groove at a point close to said side of the top, the junction of said grooves being enlarged to provide a coil forming chamber extending axially outward through the side of the block with respect to said remaining groove, said 50 grooves being only wide enough to closely receive the wire ends, and the inner side of said one groove being aligned with the inner end of said recess.

7. A tool for coil-splicing two wire ends, said 55 tool comprising a block having a substantially flat top formed with a pair of intersecting wire end receiving grooves, and a plate on said top for closing said grooves, said plate being pivoted on an axis substantially right angularly related to 60 said top, one of said grooves lying along and close to one side of said top and intersecting the remaining groove at a point close to said side of the top, the junction of said grooves being enlarged to provide a coil forming a chamber extending axial- 65 ly outward through the side of the block with respect to said remaining groove, said one of the grooves being deepened adjacent said recess so as to guide the wire end therein to the bottom of said recess. 70
